E. M. JUTKINS,
SAFETY WINDOW FOR LOCOMOTIVE CABS.
APPLICATION FILED OCT. 7, 1918.

1,324,120.

Patented Dec. 9, 1919.

UNITED STATES PATENT OFFICE.

EDGAR M. JUTKINS, OF LA JUNTA, COLORADO.

SAFETY-WINDOW FOR LOCOMOTIVE-CABS.

1,324,120.

Specification of Letters Patent.

Patented Dec. 9, 1919.

Application filed October 7, 1918. Serial No. 257,164.

To all whom it may concern:

Be it known that I, EDGAR M. JUTKINS, a citizen of the United States, residing at La Junta, in the county of Otero and State of Colorado, have invented certain new and useful Improvements in Safety-Windows for Locomotive-Cabs, of which the following is a specification, reference being had to the accompanying drawings.

10 This invention relates to certain improvements in safety windows for locomotive cabs, and it is an object of the invention to provide a window of this general character having novel and improved means whereby 15 the same may be readily and conveniently moved into an open or closed position in accordance with the occasions of practice so that an engineman within the cab may have a clear vision of the trackway in advance of 20 the locomotive.

It is also an object of the invention to provide a novel and improved window of this general type which may be easily opened and closed with but little exposure of 25 the engine crew to the elements, and which fully meets with the requirements of the Interstate Commerce Commission of the United States.

A further object of the invention is to provide a window of this general character having novel and improved means whereby a 30 broken glass may effectively and quickly be replaced.

The invention consists in the details of 35 construction and in the combination and arrangement of the several parts of my improved window, whereby certain important advantages are attained and the device rendered simpler, less expensive and otherwise 40 more convenient and advantageous for use, as will be hereinafter more fully set forth.

The novel features of my invention will hereinafter be definitely claimed.

In order that my invention may be better 45 understood, I will now proceed to describe the same with reference to the accompanying drawings, wherein:

Figure 1 is a fragmentary view partly in elevation and partly in section illustrating 50 a safety window constructed in accordance with an embodiment of my invention, the window being in an open position:

Fig. 2 is a fragmentary view partly in elevation and partly in section illustrating 55 my improved window in closed position;

Fig. 3 is an enlarged sectional view taken

through my improved window as herein described;

Fig. 4 is a view partly in elevation and partly in section illustrating the operating 60 member herein employed;

Fig. 5 is a view in top plan of the link included in the operating mechanism of the window.

Fig. 6 is a view in elevation illustrating a 65 modified form of frame adapted to be employed in connection with my improved window, a part being omitted; and

Fig. 7 is a fragmentary view in elevation of the inner face of the outer portion of the 70 frame as illustrated in Fig. 6.

While in practice two windows constructed in accordance with an embodiment of my invention are to be employed, one at each side of the cab, the present disclosure is limited to but one window and its concomitant 75 parts.

As disclosed in the accompanying drawings, D denotes a door of a well known type and which is arranged at the front of a locomotive cab at one side thereof, and which is provided with a window opening W which permits a member of the engine crew to have a clear vision of the trackway in advance of the locomotive. Coacting with the window 85 W is a safety window S mounted for swinging movement in a horizontal plane and which moves into open position in a direction opposite to the movement of the door D when being opened. In other words, the 90 window swings in a direction away from the boiler of the locomotive so that when the window S is opened or partially opened, the draft entering within the cab through the opening W will be deflected by the window 95 S toward the boiler so that the engineman will be protected against the resultant draft.

In the present embodiment of my invention the window S has an end portion suitably secured, as at 3, to the flattened portion 100 2 of the vertically disposed rock shaft R, so that the window S will move in unison with and in the same general direction as the rock shaft.

The shaft R is rotatably supported at its 105 opposite end portions by the bearings 4 bolted or otherwise affixed to the top and bottom portions of the frame of the door D.

The shaft R is held against endwise movement through the medium of the collars 5 110 arranged upwardly of the bearings 4 and said collars 5 are affixed to the shaft R by

the cotter pins 6 directed through the collars and the shaft R.

In the present embodiment of my invention the upper end portion of the shaft R is provided with a rock arm 7 terminating in an upstanding extension 8. The extension 8 is loosely directed through an eye 9 formed at one end portion of a link 10, and said link is held in applied position relative to the extension 8 through the medium of a collar 11 fixed to said extension below the link through the medium of a key 12.

The opposite end portion of the link 10 is also provided with an eye 13 which extends within the kerf of the forked or bifurcated end portion of an elongated member or rod 15. Carried by the forked or bifurcated end portion of the member or rod 15 is a pin 14 which is loosely directed through the eye 13 so that upon endwise movement being imparted to the member or rod 15 the rock shaft R will be caused to rotate through the medium of the link 10 and the rock arm 7.

The major portion of the member or rod 15 is round in cross section, and the end portion of said member or rod remote from the shaft R is flattened as indicated at 17. Bolted or otherwise secured to the portion 17 of the member or rod 15 is a depending operating member M substantially at right angles to the member or rod 15.

The member M comprises an elongated member bent into the form of a U with the upper or free end portions of the side members 18 overlying the opposite sides of the portion 17 of the member or rod 15, and secured thereto by the bolts 19 or the like.

The member M affords a loop which bridges the horizontally disposed plate 20 secured at its opposite end portions to the blocks 21 suitably anchored to the adjacent side or wall of the cab. The side members 18 of the member M are maintained in fixed spaced relation by the bolts 22, and one of said bolts is adapted to seat within the notches 23 and produced in the upper marginal portion of the plate 20, and which seats within said notches by gravity. The coaction between the member M and the plate 20 permits the window S to be effectively locked in closed or full open position, or in various intermediate positions.

Suitably secured to the lower end portion of the member M is a filler block 24 which is shaped to afford a comfortable hand grasp or hold so that the desired endwise movement may be imparted to the member or rod 15 by a member of the engine crew with convenience and facility.

The member or rod 15 is also slidably disposed through a guide 25 suitably attached to the adjacent side or wall of the cab, and which serves as a support for the forward end portion of said member or rod 15. It will be self-evident that the coaction be-

tween the member M and the plate 20 will result in the desired support for the rear portion of said member or rod 15.

As herein set forth, the safety window S comprises a frame F substantially U-shaped in form with longitudinal members *a* horizontally disposed. The adjacent marginal portions of the frame are defined by inwardly directed flanges 26 and the outer end portions of the flanges of the side members *a* are connected by the transversely disposed member 27 substantially U-shaped in cross section and having the outer side member *b* of less width than the inner side member *c* so that the insertion or removal of the glass panel P may be facilitated, and with the possibility of breakage of said panel during its insertion or removal in the frame substantially eliminated.

The glass panel P when applied has an end portion disposed between the members *b* and *c* of the member 27 and also bears against the flanges 26.

Between the longitudinal flanges 26 is a yoke 28 having its free end portions pivotally engaged with said longitudinal flanges 26 through the medium of clamping bolts 29 and the intermediate portion 30 is defined by an inwardly directed flange 31 which, when the yoke 28 is swung inwardly of the frame 25 contacts with the end portion of the panel P remote from the member 27. When the yoke 28 is in this position it is held thereat by tightening the clamping bolts 29. When it is desired to remove the panel P for any cause, it is only necessary to loosen the bolts 29 and swing the yoke 28 outwardly. With the yoke 28 in this position a new panel P can be readily applied.

As is particularly illustrated in Figs. 6 and 7, I disclose a modified form of frame for use in connection with my improved window, and wherein the bottom portion is partially cut away so that the lower portion of the frame will afford no obstruction across the cab door. In the form of invention as disclosed in Fig. 6 the frame F' substantially rectangular in form with its lower longitudinal member *a'* cut away throughout its major portion so that when the frame overlies the door or more particularly the panel thereof until the upper horizontal *a''* will obstruct the vision. The members *a'* and *a''* together with the end members *b'* of the frame have their outer margins defined by the inwardly directed flanges 26'. The inner member *b'* is adapted to be suitably attached to the rock shaft R and coacting with said connected end portion of the frame F' is a yoke 28' of substantially the same construction and operating in substantially the same manner as the yoke 28 hereinbefore referred to. Secured to the outer member *b'* is a member 27' substantially U-shaped in cross section and

otherwise similar in construction to the member 27 hereinbefore referred to.

From the foregoing description, it is thought to be obvious that a safety window for locomotive cabs constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

- 20 1. In combination with a locomotive cab having a hinged door at the front and one side thereof, said door being provided with a window opening, and a window supported for swinging movement in substantially a horizontal plane and coacting with the window opening in the door, said window and door having swinging movement in reverse directions.
- 25 2. In combination with a locomotive cab having a hinged door at the front and one side thereof, said door being provided with a window opening, and a window supported for swinging movement in substantially a

horizontal plane and coacting with the window opening in the door, said window and 35 door having swinging movement in reverse directions, said window being supported independently of the door.

3. In combination with a locomotive cab having a hinged door at the front and one 40 side thereof, said door being provided with a window opening, a window supported for swinging movement by the cab independently of the door, said window coacting with the window opening in the door and having 45 swinging movement in a direction reverse to the door, and means supported by the cab for imparting swinging movement to the window independently of the door.

4. In combination with a locomotive cab 50 having a hinged door at the front and one side thereof, said door being provided with a window opening, a vertically disposed shaft supported by the cab in close proximity to the door, a window coacting with the 55 window opening in the door and secured to the shaft, and means for rotating the shaft to swing the window toward or from the door, said window and door having swinging movement in reverse directions. 60

In testimony whereof I hereunto affix my signature in the presence of two witnesses.

EDGAR M. JUTKINS.
